Application September 24, 1940, Serial No. 95,343

Term of patent 3½ years

To all whom it may concern:

Be it known that I, Hilda Altmark, a citizen of the United States, residing at 101 Central Park West, New York city, in the county of New York and State of New York, have invented a new, original, and ornamental Design for a Dress, of which the following is a specification, reference being had to the accompanying drawing, forming part thereof.

Figure 1 is a front view of a dress, showing my new design; and

The characteristic feature of my design resides in the combination on the specific dress disclosed of the looped piping around the peplum portion of the dress in association with the bow trimmed sleeves and the triangular piping around the neck thereof, all as shown.

I claim:

The ornamental design for a dress, substantially as shown and described.

HILDA ALTMARK.
